9220 $\frac{1}{2}$ X

Peters & Dean,

Rotary Pump.

Patented Oct. 31, 1835.

9220 1/2 X

Oct 31. 1835

Charles Peters and Benjamin Dean of Poughkeepsie N.Y.
Letters Patent

The Schedule referred to in these Letters Patent and making part of the same
containing a description in the words of the said Charles Peters & Benjamin
Dean themselves of their improvement in the Rotary Pump.

To all to whom these presents shall come. Know Ye that we, Charles Peters and Benjamin Dean of the Village of Poughkeepsie in Dutchess County and State of New York, have jointly invented and
brought into use certain new and useful improvements in the construc-
tion of a Rotary Pump, by which the lifting and forcing of water or other
liquids, may be effected separately or conjointly, by a continuous, Rotary
motion, with more ease, with the same power, and greater abundance
than hath hitherto been before known; and that the said improvements and the
methods of effecting, applying, and using the same, are set forth and
shown in the following description, and in the drawings annexed
to and making part of this Specification, in such full, clear, and exact
terms as to distinguish the same from all other improvements before known.
Illustration Figure 1. represents a vertical projection of one side of the
circle or shell of the pump, with its wheel, valves, pipe, and other parts
in skeleton, the covering plate on that side being removed, to exhibit the
interior parts. Figure 2. represents a vertical cross section of
the same, with also induction, and education pipes, the crank and
spindle or arbor. The Letters of reference apply to the similar parts
in both figures, Number 1. and number 2. A. A. is the standard
pipe which may be connected at the foot in any convenient manner
with another pipe by being soldered or secured on or by any other means
this last mentioned pipe leading to the liquid in the well, tank, cister-
nacle or other vessel. B. B. is a cylindrical box having two flat
sides, secured in any convenient manner, to the edge of the ring within
this box is the Rotary cylinder. C. having an extrodning end three
arms, and according to an arbor or spindle D. and having the two flat
external sides carefully fitted to work close to the side plates of the box.

on the periphery of the cylinder C. are hinged valves, c.c.c. which are to be shut down by the slide valves f. as the valves pass along, or under it and the valves are to be again opened out by the operation of lifting levers, g.g.g. shown in figure 1. by dotted lines. These levers at the inner and outer, over and are regulated by the cam h. Also shown by dotted lines, as fixed on the lower plate on that side, and having room in a counterbore space in the cylinder C. to lie into. The levers g.g. g. have each a small roller fitted into each of their ends, by a motion to revolve on pins, and are fixed in, near one side of the cylinder C. immediately under the valves c.c.c. are openings shown by dotted lines and cut as large as the material will allow, into the spaces between the arms and body of the rotary cylinder C. and in the cone platen that side is an opening into the induction pipe i. whose domed flange covers that end of the spindle d. and also the induction opening.

When the machine is to be used, the handle K. is to be turned back as to project the cylinder C. and valves, c.c.c. in the direction of the arrows, by these parts being fitted closely the air will draw out of the pipe a. and the fluid below will rise therein and go under each valve in succession through the openings and into the interior of the cylinder C. in the course shown by the dotted arrows, whence by the continuance of the operation the fluid will be driven out through the induction pipe i. Figure 2. This machine may be made of any convenient metal according to the size required and the description of fluid matter it is intended to operate on. Bell metal is best for general use. The induction and induction and induction pipes must be in proportion to the size and strength of the cylinder shell and wheel of the pump and these should be in proportion to the quantity of liquor intended to be raised and delivered in a given space of time and the power to be applied should be in proportion to the whole.

The number of valves should not exceed four nor be less than two. There has been found the most convenient a half number.

The larger shell of the pump may be from 3 inches up to 12 inches in diameter, according to the size for which the pump is designed.

When the wheel or wheel of the pump is very large, the other parts made of copper conform in size and strength. This pump may be made of a size and strength sufficient to deliver a very large column of water much larger than from common pumps.

We do not claim as our invention any of the parts of the above described pump separately, but we claim as our invention to implement the openings of the holes in the wheel leading to and from its center for the passage of the liquid and to combining them with the slots which cover them, and with the other parts of said pump adjusted and placed in manner aforesaid so to take all the water which comes into the pump to the center of the wheel and thence deliver it. This plan of taking the liquid to the center of the wheel and then delivering it as well as the mode of effecting that object we believe to be new and we have found it very useful.

A pump constructed upon our aforesaid plan is much more simple, much easier kept in order, and much more powerful and will use much less than the common strong pump. By fitting a pipe upon to the outlet and closing the ordinary aperture at which the water or liquid is delivered, it may be forced into any room in the house or to almost any height. It acts in our hands.
